Primary Examiner—Alan P. Douglas*Assistant Examiner*—R. Spear*Attorney, Agent, or Firm*—Brenda L. Morrison[57] **CLAIM**

The ornamental design for an oil spout, as shown and described.

DESCRIPTION

FIG. 1 is a perspective view of an oil spout showing my new design;

FIG. 2 is a perspective view from the opposite end thereof;

FIG. 3 is a left side elevational view thereof, the right side elevational view being a mirror image of the left side elevational view; and,

FIG. 4 is a bottom elevational view thereof.

FIG. 1

FIG. 2

FIG. 3

FIG. 4
